3 Claims

This invention relates to a method for scarfing the surface of a metal body, and more particularly to improvements on a method of trapping and disposing of the molten slag produced upon the surface of the metal body during the thermochemical reaction, by the use of a fluid stream which is discharged so as to skim across the surface of the body at high velocity.

The basic method for trapping and removing slag produced during scarfing is disclosed by I. P. Thompson et al. in U.S. Patent 2,465,297. As disclosed therein, during the thermochemical scarfing process a stream of oxidizing gas is directed obliquely against a reaction zone of molten metal which has previously been formed upon the surface of the body. By so doing, a thermochemical reaction is produced, which continues longitudinally along the surface of the body as relative movement is produced between the body and the stream of oxidizing gas. As a result of this thermochemical scarfing reaction, a molten slag is produced which must be removed from the surface of the body. This is accomplished according to Thompson et al. by directing a stream of fluid, e.g. water, at high velocity, in such manner as to skim across the surface of the body and thereby impinge against and deflect and remove the slag off the surface thereof. The fluid stream also breaks the slag into small particles, chills them, and carries them from the body surface into a slag chute.

While the Thompson et al. method has been used successfully for many years, it is not entirely satisfactory since it fails to trap the fine spray of slag particles that are deflected from the main fluid stream, as well as from the reaction itself. A certain portion of the slag particles also penetrates through the fluid stream due to their momentum. In addition, a considerable quantity of slag spray is deflected in directions away from the slag chute, causing a substantial buildup and accumulation of slag upon the scarfing machine, slag target, roll table and smoke hood. Such buildup of slag necessitates frequent maintenance and consequently causes downtime of the machine.

It is the principal object of this invention to provide an improved method of trapping and removing slag produced during a thermochemical scarfing reaction, such that substantially all of the slag produced will be removed from the scarfed body, with little, if any, being deflected against the surfaces of the scarfing machine, slag target, roll table, smoke hood and other parts of the work area.

According to the present invention, a deflector surface is positioned across the path of relative movement of the body to be scarfed, at a point adjacent the reaction zone, and in the path of the slag produced. A fluid stream, e.g. water, is then flowed upon the surface of the

2

deflector in order to maintain it wetted. The effect of the wetted deflector surface is remarkable in that the particles of flying slag which strike the surface do not stick to it. Instead they are immediately solidified and washed over the deflector surface into a slag chute. Moreover, the surface prevents the slag particles from penetrating through the fluid stream and escaping into the work area. While the deflector may be flat, when scarfing relatively wide metal bodies it is preferable to have it curve shaped, with the cavity thereof facing the reaction zone.

In the drawing:

FIGURE 1 is an isometric elevational view of a metal body being scarfed, illustrating a preferred embodiment of the invention, utilizing a wetted curve shaped deflector and

FIGURE 2 is an isometric elevational view similar to FIGURE 1, but illustrating another embodiment of the invention, utilizing a flat deflector surface.

Referring to FIGURE 1, the metal body to be scarfed is supported upon and moved by roll table R toward a scarfing unit M. A molten puddle of metal is formed upon the surface of the body at reaction zone Z, by preheat flames from the scarfing unit M. Thereafter a sheet-like stream of oxidizing gas S, e.g. oxygen, is directed obliquely against the molten puddle to cause a thermochemical reaction. Relative movement is then produced between the metal body W and the oxidizing gas stream S so as to continue the reaction longitudinally along the surface of the body. As the scarfing reaction proceeds, molten slag is produced and projected forwardly and upwardly from the reaction zone Z, as shown generally by the arrows.

In order to trap and remove the slag which is produced, a surface 12 is positioned across the path of relative movement at a point adjacent the reaction zone Z and in the path of the projected slag. A stream of fluid, e.g. water, is flowed at high velocity over the surface 12 in order to maintain the same wetted continuously.

As the particles of molten slag strike the wetted deflector surface they are immediately chilled, solidified, and washed along the wetted surface area into a slag chute 14. The surface 12 backing up the fluid stream acts as a shield to prevent a portion of the projected slag from penetrating through or becoming deflected by such stream.

The surface 12 is preferably curved-shaped with the cavity therein facing the reaction zone Z. This configuration is particularly effective when scarfing relatively wide metal bodies, i.e. slabs, in that it forms a pocket to maintain the coherency of the fluid stream over the entire length of the surface.

The diameter of the curve-shaped surface will usually be of the order of 6 to 12 inches, over which a flow of about 700 to 1,000 gallons of fluid per minute is maintained during scarfing.

As shown in FIGURE 2, when scarfing relatively narrow metal bodies, e.g. billets, flat surfaces 16 may be used to back up each fluid stream with good results. When scarfing a 10 inch square billet, for example, four nozzles N, each having a diameter of 1½ inch and discharging

about 200 g.p.m. each, were found highly effective in trapping and removing the slag produced during scarfing.

What is claimed is:

1. In a thermochemical scarfing process wherein an oxidizing gas is directed from a scarfing unit against a reaction zone of molten metal on the surface of a metal body to produce a thermochemical reaction thereon, and relative movement is produced between such scarfing unit and the body for continuing such reaction along the length of such surface, the improvement in trapping and disposing of the molten slag produced during such reaction from the scarfing area which comprises: positioning a deflector surface across the path of relative movement at a point adjacent the reaction zone and in the path of the slag produced, and flowing a fluid stream over 15 said surface to maintain the same wetted.

2. In a scarfing process as claimed in claim 1 wherein said surface is curved-shaped with the cavity therein facing the reaction zone.

5 3. In a scarfing process as claimed in claim 2 wherein said surface is maintained cool by water flowing thereupon and comprising said fluid stream.

UNITED STATES PATENT OFFICE
CERTIFICATE OF CORRECTION

Patent No. 3,436,276

Dated April 1, 1969

Inventor(s) I.P. Thompson

It is certified that error appears in the above-identified patent and that said Letters Patent are hereby corrected as shown below:

In column 2, line 4, "solified" should read -- solidified
Column 2, line 25, after the word "is" cancel "di^l" and
insert -- directed obliquely against the molten puddle
to cause a --.

Column 2, line 32, "proceds" should read -- proceeds --.

Signed and sealed this 19th day of October 1971.
